UNITED STATES PATENT OFFICE

ARTHUR G. SANDEN, OF SOUTH BELLINGHAM, WASHINGTON

DRAFTING INSTRUMENT

Application filed March 21, 1929. Serial No. 348,874.

This invention relates to drafting instruments and has special reference to that type of instrument known as a draftsman's triangle.

5 It is a matter of common knowledge that the most meager draftsman's equipment includes a 45° triangle, a 60° triangle, a protractor, several irregular curves, and dividers or compasses. If unusual angles are to be 10 drawn either additional special triangles must be provided, or resort must be made to use of the protractor to lay off these angles. The latter course is uniformly unsatisfactory and consumes much valuable time. Also special 15 triangles are usually provided to aid in expediting section lining.

The primary object of this invention is to combine this multiplicity of individual instruments in a single device that will be easy 20 to handle, easy of interpretation, thoroughly accurate, and inexpensive to manufacture.

These objects are attained in the instrument which is the subject-matter of this invention, which is fully described in the following specification, clearly shown in the accompanying drawing, and accurately defined in the appended claims.

The accompanying drawing shows a plan view of my new drafting instrument, which 30 is formed with a flat body of the usual thickness of such instruments, and preferably of transparent material such as clear celluloid, phenol condensation product, or like material. It will be understood however that it may 35 be made of wood, hard rubber or other non-transparent material.

The instrument is formed with the usual base 1, which is considerably shorter than the vertical side 2, and at a right angle thereto. 40 The third, or hypotenuse, side 3, is formed by two right lines that are generated from a point 4 practically midway its length; one of said right lines 5 meeting the vertical side at an angle of 45° and the other right line 6 45 meeting the base at an angle of 60°. The two right lines 5 and 6 subtend an angle of 165° at their meeting point 4.

In the body portion of my instrument is formed an elongated opening 7, one longitudinal side 9 of which is formed mainly by

the other curve 10 of a protractor generated about the point 4 by the radius 8. This protractor is graduated in the conventional manner. The other longitudinal side is a right line 11 which if extended would include the vertex 24 of the triangle. This line is disposed at an angle of 15° with respect to the vertical side 2, and 75° with respect to base 1. The upper portion 12 of the side 9 becomes tangent to the protractor curve approximately at the point marked 45°, then develops into an irregular curve meeting the side 11 at 13. The bottom portion of opening 7 is bounded by an irregular curve 14 meeting side 9 at 15 and side 11 at 16.

Within that portion of the body of my new instrument described by radius 8 is a large irregular curve opening 17, a small irregular curve opening 18, and a series of circular openings 19, 20, 21 and 22 of varying diameters. Parallel with side 11 is a series of openings 23 which are capable of use either in drawing cross-section lines, or in describing circles, and arcs thereof.

I claim—

1. A drafting instrument consisting of a body formed with a base, a side at 90° thereto, and a third side formed by two right lines meeting at an angle of 165°, said body having an irregular curve opening therein, one side of said opening being for a major portion of its height, a right line disposed at an angle of 75° with respect to said base, the opposite side of said irregular curve opening being formed for a major portion of its extent by a segment of a circle whose center is the meeting point of said two right lines.

2. A drafting instrument consisting of a body formed with a base, a vertical side at 90° thereto, a third side meeting said vertical side at an angle of 45° and said base at an angle of 60°, and subtending an angle of 165°, said body having an opening therein, one side of which is a right line disposed at an angle of 75° with respect to said base which if extended would include the vertex of said angle of 45° and whose opposite side is an irregular curve, a major portion of which is the segment of a circle generated about the vertex of the 165° angle.

3. A drafting instrument consisting of a body formed with a base, a side at 90° thereto, a third side formed by two right lines meeting at an angle of 165° , said body having
5 an opening therein the major portion of one side of which is a right line disposed at an angle of 75° with respect to said base, the opposite side of said opening being an irregular curve a major portion of which is the arc of a
10 circle and a tangent thereto, the center of said arc of a circle being the meeting point of said two right lines.
